US00D863363S

(12) **United States Design Patent** (10) **Patent No.:** **US D863,363 S**
(45) **Date of Patent:** **** Oct. 15, 2019**

(54) **HANDLE FOR PUMP**

(71) Applicant: **Ontel Products Corporation**, Fairfield, NJ (US)

(72) Inventor: **Ross Exley**, Morristown, NJ (US)

(73) Assignee: **Ontel Products Corporation**, Fairfield, NJ (US)

(**) Term: **15 Years**

(21) Appl. No.: **29/646,024**

(22) Filed: **May 1, 2018**

(51) LOC (12) Cl. **15-03**

(52) U.S. Cl.

(57) **CLAIM**

The ornamental design for a handle for a pump, as shown.

DESCRIPTION

FIG. 1 is a perspective view of a handle for a pump according to the present disclosure;

FIG. 2 is a front view of the handle for the pump of FIG. 1; FIG. 3 is a rear view of the handle for the pump of FIG. 1; FIG. 4 is a left side view of the handle for the pump of FIG. 1;

FIG. 5 is a right side view of the handle for the pump of FIG. 1;

FIG. 6 is a top plan view of the handle for the pump of FIG. 1;

FIG. 7 is a bottom plan view of the handle for the pump of FIG. 1;

FIG. 8 is a second perspective view of the handle for the pump of FIG. 1; and,

FIG. 9 is a third perspective view of the handle for the pump of FIG. 1.

The broken lines shown represent unclaimed subject matter and form no part of the claimed design.

1 Claim, 8 Drawing Sheets
